Patented Nov. 29, 1921.

Inventor,

George L. PERUSSE
By his Attorneys

Kenyon & Kenyon

UNITED STATES PATENT OFFICE.

GEORGE L. PERUSSE, OF CHICAGO, ILLINOIS, ASSIGNOR TO O-SO-EZY PRODUCTS COMPANY, A CORPORATION OF ILLINOIS.

MOP.

1,398,567.

Specification of Letters Patent. Patented Nov. 29, 1921.

Application filed May 16, 1918, Serial No. 234,842. Renewed April 27, 1921. Serial No. 464,907.

To all whom it may concern:

Be it known that I, GEORGE L. PERUSSE, a citizen of the United States, residing at Chicago, county of Cook, State of Illinois, and whose post-office address is 120 So. St. Louis Ave., Chicago, Illinois, have invented certain new and useful Improvements in Mops, of which the following is a specification.

My invention relates to mops.

10 An object of my invention is to produce an article of this character consisting of the least number of parts and which will have greatest simplicity together with the necessary endurance to meet the usual usage to 15 which such an article is subjected.

Further objects and advantages will be apparent upon reading the following description taken in connection with the accompanying drawings forming a part of this application, and in which—

Figure 1 is a perspective view of the mop embodying my invention; and

Fig. 2 is a section through the line 2—2 of Fig. 1.

25 Referring to the drawings, it will be seen that my device consists of a horizontal carrier plate 1 with a two-ply flange extending upwardly therefrom. This flange consists of a ply 2 and a ply 3 with the opening extending downwardly. It is preferred that this flange should be vertical or substantially so. Near the center of the carrier plate 1 is a raised portion 4 to which the handle socket 5 is connected. This socket is connected by means of integral portions 6 extending through the plate 1 and bent so as to hold the handle socket in place.

40 The handle socket is made of a single piece of metal having two members 7 attached to the plate 1 and a tubular portion 8 for the handle. This tubular portion 8 is threaded at 9 so that the handle which is likewise screw-threaded, may be screwed into the socket.

The mop itself may be of the usual construction. The upper part of the mop is placed between the plies 2 and 3 which are afterward pressed together so as to hold the mop in place by friction. The flange extends entirely around the plate as does 50 likewise the mop which is held between the plies of the flange.

55 The head is provided with a series of holes 11 around the circumference thereof and near where the flange projects upwardly from the plate. These holes are provided for the purpose of permitting polishing material to pass therefrom into contact with the mop material hanging downwardly from the flange.

60 From the foregoing description, it will be evident that my device as illustrated in the drawings comprises only three parts; the head comprising the carrier plate and the integral flange; the handle socket, and the 65 mop.

It will also be apparent that the device is of substantial character, easily manufactured and capable of withstanding the necessary hard usage to which articles of this 70 character are subjected.

Having described my invention, what I claim as new and desire to secure by Letters Patent is:

75 In a device of the character described, the combination of a circular mop head of sheet metal comprising a carrier plate provided with an upstanding portion extending therearound, said portion being integral with said plate, and a depending flange integrally 80 connected with the upper edge of said upstanding portion and a mop extending around said portion and clamped between it and said flange.

85 In testimony whereof, I have signed my name to this specification.

GEORGE L. PERUSSE.
